UNITED STATES PATENT OFFICE.

ARTHUR J. CHARON, OF GREENFIELD, MASSACHUSETTS.

NECKTIE.

964,755.

Specification of Letters Patent. Patented July 19, 1910.

Application filed September 4, 1908. Serial No. 451,688.

To all whom it may concern:

Be it known that I, ARTHUR J. CHARON, a citizen of the United States, residing at Greenfield, in the county of Franklin and State of Massachusetts, have invented new and useful Improvements in Neckties, of which the following is a specification.

This invention relates to new and useful improvements in neckties and it is primarily the object of the invention to provide a novel device of this character wherein the scarf end of the tie is always assured of a proper effect.

It is also an object of the invention to provide a novel device of this character wherein the scarf or broad portion of the tie is so formed as to give the appearance of two end portions.

Furthermore it is an object of the invention to provide a novel device of this character including means whereby the narrow end of the tie can be readily and conveniently concealed in order that the effect of the tie will not be marred.

The invention also has for an object to provide a novel device of this character which is formed from a continuous piece of material.

Further, it is an object of the invention to provide a novel device of this character which will be simple in construction, efficient and advantageous in practice and comparatively inexpensive to manufacture.

With the above and other objects in view the invention consists in the details of construction and in the arrangement and combination of parts to be hereinafter more particularly referred to.

In describing the invention in detail reference will be had to the accompanying drawings forming part of this specification wherein like characters of reference denote corresponding parts in the several views and in which,

Figure 1 is a view of the tie arranged as when worn showing the finished effect; Fig. 2, is a view in front elevation of the tie extended; Fig. 3, is a view in rear elevation of Fig. 2; and Fig. 4, is a view in plan of the blank, the folds given the blank being indicated by dotted lines.

In the drawings 1, denotes the broad end

or scarf portion of the tie, 2 the narrow end portion and 3, the intermediate or neck portion. These are formed from a single piece 55 of material and in the manner indicated by Fig. 4.

In forming the tie the scarf portion of the tie is of sufficient width and has its edges *a* and *b* arranged on converging lines, the 60 edge *b* forming one of the edges of the intermediate portion 3, and narrow portion 2. The lower edge of the scarf is serrated or arranged on an irregular line as indicated at *c*. Each of the edges *a* and *b* are notched 65 at opposed points, as at *d*, said notches being positioned between the center and the upper edge of the scarf portion. In forming the tie the scarf portion is bent or folded inwardly on the line indicated by *e*. The 70 scarf portion is then plaited on the line *f* and *g*. This plait brings the edge formed by the fold *e* at a point indicated by the line *h*. The edge portion *b* is then folded 75 inwardly on the line *h* and overlaps the plait 75 to which it is secured by suitable stitching to which it is secured by suitable stitching as indicated at *j* in Fig. 3. The folding of the edge portion *b* extends through the intermediate portion 3 and the narrow portion 2. The article shown in Figs. 2 and 3 results. 80 This folding also brings the notches *d* in register and they are then stitched as indicated at *k* to form the opening *m*. By this arrangement it is thought to be obvious that a tie is provided having its scarf portion 85 formed of four plies, the inner ply being provided with an opening which, in practice is intended to have passed therethrough the narrow portion of the tie. It is also to be stated that the edge portion of the ply 90 formed by the plait is secured to the opposed ply thereof by an invisible running stitch indicated by *o* in Figs. 2 and 3. It is thought to be apparent that the irregular edge *c* produces the finished effect of the tie as indicated by 4 in Figs. 1 and 2.

In use the tie is formed into a four-in-hand in the usual manner and the narrow portion 2 thereof is passed in between the plies of the scarf of the tie through the 100 opening *m*. By this means a proper effect of the tie is always assured. It might also be well to state at this point that the narrow portion of the tie is provided within its

10
folds with suitable reinforcing material to permit the insertion of the narrow portion through the opening *m*.

I claim:—

- 5 As a new article of manufacture, a necktie formed of a single piece of material, the scarf portion of the material having a lateral extension, said extension being folded upon itself on longitudinal lines, the longi-

tudinal edges of the scarf portion being provided with alining notches to form an opening when the scarf portion is folded.

In testimony whereof, I affix my signature in the presence of two witnesses.

ARTHUR J. CHARON.
